Primary Examiner — Brett Miller*Assistant Examiner* — Rani J Abdallah(74) *Attorney, Agent, or Firm* — The Belles Group, P.C.(57) **CLAIM**

The ornamental design for a bottle, as shown and described.

DESCRIPTION

FIG. 1 is a front perspective view of a bottle according to a first embodiment of the new design;

FIG. 2 is a front view thereof, the rear view being identical to the front view;

FIG. 3 is a right side view thereof, the left side view being identical to the right side view;

FIG. 4 is a top view thereof;

FIG. 5 is a bottom view thereof;

FIG. 6 is a front perspective view of a bottle according to a second embodiment of the new design;

FIG. 7 is a front view thereof, the rear view being identical to the front view;

FIG. 8 is a right side view thereof, the left side view being identical to the right side view;

FIG. 9 is a top view thereof; and,

FIG. 10 is a bottom view thereof.

The broken lines illustrate portions of the bottle that form no part of the claimed design.
